[57] CLAIM

The ornamental design for a compartmented hiking stick, as shown and described.

DESCRIPTION

FIG. 1 is a side elevational view of a compartmented hiking stick showing my new design.

FIG. 2 is a front elevational view thereof.

FIG. 3 is a side elevational view similar to FIG. 1, but showing the opposite side thereof.

FIG. 4 is a rear elevational view thereof.

FIG. 5 is a bottom plan view thereof.

FIG. 6 is a top plan view thereof.

FIG. 1 FIG. 2 FIG. 3 FIG. 4
